UNITED STATES PATENT OFFICE.

HERBERT ELLIOTT, OF TORONTO, ONTARIO, CANADA.

DESIGN FOR A STATUETTE OR SIMILAR ARTICLE.

53,119.

Specification for Design.

Patented Mar. 25, 1919.

Application filed December 20, 1918. Serial No. 267,662. Term of patent 3½ years.

To all whom it may concern:

Be it known that I, HERBERT ELLIOTT, a subject of the King of Great Britain, residing at Toronto, in the county of York, in the Province of Ontario, in the Dominion of Canada, have invented a new, original, and ornamental Design for a Statuette or Similar Article, of which the following is a specification, reference being had to the accompanying drawing, forming part thereof.

In the drawing;

Fig. 2 is a perspective view of the same viewed at a different angle.

I claim:—

The ornamental design for a statuette or similar article, as shown.

Signed at Toronto, in the county of York, in the Province of Ontario, in the Dominion of Canada, this 14th day of December, 1918.

HERBERT ELLIOTT.
